FEEDING MECHANISM FOR BOTTLE
PACKING MACHINESWallace D. Kimball, Jackson Heights, N. Y., as-
signor to Standard-Knapp Corporation, Long
Island City, N. Y., a corporation of New York

Application February 11, 1938, Serial No. 189,917

14 Claims. (Cl. 226—14)

This invention relates to machines for packing articles in cases for shipment or storage, and, more especially, to mechanism for automatically feeding the cases into proper position to receive the charge of articles and then releasing or discharging the filled cases from the machine.

Articles such as bottles or cans of food products or beverages, as well as packages of cereal, soap and the like are ordinarily packed for shipment in cases made of corrugated board, fibre-board, wood, or other suitable material. In one form of apparatus for packing the articles in these cases, the articles are assembled by means of appropriate mechanism to form a charge corresponding in dimensions to the size of the case to be packed and the charge is then passed by gravity through a charge-directing mechanism into the case. This charge-directing mechanism may be arranged to handle the charge with all of the articles composing the charge in contact with one another, or it may be arranged to direct or guide each one of the articles separately and individually, as is necessary in packing cell cases, that is to say, cases which are provided with suitable partitioning devices to prevent breakage or damage by mutual contact or rubbing of the articles during transit.

When the articles are to be packed in collapsible cases which are shipped to the user "in the flat," the operator of the packing machine unfolds and straightens up the cases and places them on the loading table of the packing machine by hand. There are instances, however, as, for example, in the handling of beverages such as "Coca Cola" or the like where it is desired to pack bottles containing the beverage in non-collapsible cases such as wooden trays provided with cells for the individual bottles. In such instances, that is to say, where the cases do not have to be unfolded and set up from the flat, it is desirable to arrange for the cases to be fed automatically to the packing machine.

In order to provide this automatic feed of the cases to be packed it is not a question of merely arranging a conveyor to carry a line of empty cases beneath the charge-directing mechanism of the packing machine. Not only must the cases be brought into register with the mouth of the charge-directing mechanism, but also, in order to properly direct the charge into the case, the mouth of the directing mechanism must be made to enter the top of the case, and if the cases are moved laterally into position beneath the charge-directing mechanism at the proper elevation to receive the charge, the upper edge of the case

will be above the lower portion of the charge-directing mechanism. Attempts have heretofore been made to overcome this difficulty by making the lower portion of this mechanism yielding, or flexible, so that as the case is moved laterally into position this yielding, or flexible, lower part of the charge-directing mechanism will be pushed to one side sufficiently to allow it to spring over the forward edge of the case. This arrangement, however, has been found unsatisfactory in operation, and the object of the present invention is to provide a mechanism for automatically positioning cases successively in charge-receiving position or in engagement with the charge-directing mechanism without causing a lateral displacement of the mouth of this mechanism by the case, even though it is customary to make the lower portion of this mechanism of a yielding, or flexible, nature for other reasons.

The invention will be understood from a consideration of the accompanying drawings which show one embodiment of the invention by way of example. In these drawings the invention is shown as being embodied in a machine for packing bottles such, for example, as "Coca Cola" bottles, in wooden cell cases which have individual cells, or compartments, for each bottle of the charge. It will be understood that instead of packing bottles in wooden cases, the machine is also adapted to handle cases made of other materials, such, for example, as cartons made of corrugated fibreboard and the like, and to pack therein other articles, such, for example, as either round or square cans, soap, packages of cereal, etc. In these drawings:

Fig. 1 is a plan view of such a bottle packing machine provided with the automatic box or case-feeding mechanism of the present invention, certain parts of this mechanism being omitted in this view, however, for the sake of clearness;

Fig. 2 is a view in elevation taken from the front end of the machine. The cases come in from the right and are discharged at the left of the machine as shown in this view;

Fig. 3 is a view partly in side elevation looking from the left-hand side of the machine as viewed in Fig. 1, and partly in section, the section being taken on broken line 3—3 of Fig. 5;

Fig. 4 is a view somewhat similar to Fig. 3 but looking from the opposite, or right hand, side of the machine and taken in vertical section on the plane 4—4 of Figs. 1, 2 and 6;

Fig. 5 is a transverse vertical section taken on plane 5—5 of Fig. 1;

Fig. 6 is a horizontal section taken on plane 6—6 of Fig. 5. It shows the case-feeding mechanism in plan view and in reality is a view quite similar to Fig. 1, the upper part, or packing mechanism, of the machine removed; and

Figs. 7 to 10, inclusive, are enlarged and somewhat diagrammatic views for the purpose of more clearly showing the operation of certain details of the mechanism.

In plants where such cases are used there is usually a department where the cases are made, or damaged cases are reconstructed, or cleaned, or both, and it is customary for the cases to be carried from such department by means of a roller conveyor to the packing machine. The end of such a conveyor adjacent the packing machine is indicated at 1, and it will be understood that the cases may be arranged in a chance formation on this conveyor, sometimes being spaced from one another at different distances apart, and at other times, and more usually, being in end to end contact forming a continuous line adjacent the packing machine.

The mechanism of the present invention provides for taking the empty cases one at a time from conveyor 1, elevating them into filling position within the packing machine, and then lowering them after being filled with bottles and discharging them from the machine onto a suitable conveyor by means of which the cases are carried along to the next operation or to the delivery or storage room. The filled cases are preferably lowered to the same level at which they came into the machine before being elevated to filling position.

Before describing this case-handling, or feeding, mechanism, however, the charge-assembling and packing mechanism will be described as briefly as possible. Referring to Fig. 1, the charge-assembling mechanism is indicated generally by reference numeral 2, and the charge-directing mechanism by numeral 3 (see the other figures). The bottles come into the machine on a wide belt 4 shown in Fig. 1 in four lanes 5, being held in these lanes by suitable guide bars or rails 6 mounted in fixed position above belt 4. This belt is driven by means of a drum, or roll, 7 fixed to a shaft 8 which is driven by means of a chain 9 from a sprocket 10 mounted on a low speed shaft 11 of a reduction gearing 12. The high speed shaft 13 of this reduction gearing is belt driven from an electric motor 14, and all of the power for operating the machine is supplied by this motor and delivered through the reduction gearing 12 to the low speed shaft 11 and to a second low speed shaft 15 which drives the case-feeding mechanism and which will be referred to again later.

Belt 4 carries the bottles up to a point above driving roll 7 and then delivers them onto a series of narrow supporting rails 16, the ends of which are pointed, as shown in Fig. 4 so as to extend in close proximity to the moving surface of belt 4. Four of these rails 16 are arranged midway of the lanes 5 of Fig. 1, which places them on the same spacing as the guide bars 6, which is just enough greater than the diameter of the bottles to permit the bottles to pass freely between them. A fifth member 17, which is similar in construction to rails 16, but which never serves the purpose of supporting bottles, is arranged to the right of the outside guide bar 6.

As the bottles are moved onto the supporting rails 16 by belt 4, they are maintained in upright position by means of shiftable plates 18 of the charge-assembling mechanism 2, which are fixed upon a pair of cross rods 19 in spaced relation and in alignment with the ends of the guide bars 6 and spaced apart by the same distance as the supporting rails 16.

When six bottles have been received upon each of the rails 16 between the shiftable plates 18, that is to say, a full charge, plates 18 are shifted to the right, as viewed in Figs. 1 and 5, by a distance equal to $\frac{1}{2}$ of the spacing of rails 16, thereby bringing the plates 18 into vertical alignment with rails 16 and the outside right-hand plate 18 into alignment with member 17. This causes the four rows of bottles constituting the charge to descend vertically by gravity and drop through the charge-directing mechanism 3, a part of which is constituted by the rails 16 and member 17, into a case 20 which has been appropriately positioned beneath and with respect to the charge-directing mechanism 3.

In order to provide for shifting the plates 18 bodily as a unit, the cross rods 19, upon which the plates are mounted, are pivoted at their ends upon the upper ends of four equal length arms 21, two of which are pinned to a rock shaft 22 on the right side of the machine, and two of which are pinned to a rock shaft 23 on the left-hand side of the machine. Shafts 22 and 23 are journalled in brackets on the frame of the machine. Shaft 23 on the left-hand side of the machine is somewhat longer than shaft 22, and its bearings are indicated at 24 and 25. The rocking of this shaft imparts the motion to arms 19 which causes the shifting movement of plates 18.

This rocking movement is accomplished by means of a tension spring 26 whose action is controlled by means of a disc cam 27 which is mounted upon a shaft 28 parallel with shaft 8 of the roll 7, but below the same. This shaft is driven by means of a chain 29 from a sprocket 30 on shaft 11 of the reducing gear 12. Tension spring 26 is connected at one end to a bracket 31 on the machine frame and at the other to the upper end of an arm 32 extending upwardly from a hub 33 which is loose upon shaft 23. The continuously rotating cam 27 acts upon a roller 34 which is carried at the lower end of a second arm 35 which extends downwardly from hub 33. When the control mechanism, which will be described presently, permits shaft 23 to be rocked by the tension of spring 26, roller 34 follows the contour of cam 27 and as the projection 36 of the cam rotates, the roller moves into engagement with the long dwell 37. The consequent rocking of hub 33 and arm 32 is transmitted to shaft 23 by means of a bell crank arm 38 which is keyed, or otherwise secured to shaft 23 and the upper end of which rests against the face of arm 32.

Upon the continued rotation of cam 27, roller 34 again rides upon the projection 36 of the cam, thus returning arm 35 to its original position and the movement thereby imparted to arm 32 is transmitted to shaft 23 through an arcuate bolt 39 and a compression spring 40 thereabout shown in Fig. 5. Bolt 39 is secured at its inner end in the arm 32 and one end of spring 40 bears against the head of the bolt and the other end against the side of bell crank arm 38. The other arm 41 of bell crank arm 38 bears against a part of the machine frame and serves as a stop for limiting

the shifting of the plates 18 under the action of tension spring 26.

It will be understood that spring 26 and cam 27 are permitted to shift cross rods 19 and plates 18 to cause a charge of bottles to drop into a case only when there is a full charge of bottles between the plates 18, or, that is, within the charge-assembling mechanism 2. The mechanism to control this action will now be described.

As the bottles are shoved by belt 4 onto rails 16 and into charge-forming position between the plates 18, the friction of the bottles in lanes 5 on belt 4 presses the bottles between the plates forward, and when all four rows are filled with bottles, the foremost bottle of each row engages and moves a tripping lever 42, one of which is at the head of each row in alinement with the rails 16. These levers move against tension springs 43 and shift latches 44 to the right, as shown in Fig. 4, and out of engagement with a latch bar 45. These tripping levers 42 are pivoted on a cross shaft 46, and latch bar 45 extends crosswise of the end of the machine, as shown in Fig. 1 and is carried on two short lever arms 47 which are pinned to another cross shaft 48 which is parallel with shaft 46. Thus, when all four rails 16 of the charge-assembling mechanism are filled with the bottles, all four latches 42 are released from latch bar 45.

Latch bar 45, however, is still held in its original position unless the case 20 has been raised to its appropriate position with respect to the charge-directing mechanism, as shown in Fig. 5, by means of the carton elevating device which will be described later. This is accomplished by means of a fifth tripping lever 49 which, instead of being actuated by the bottles, is actuated by the raising of the elevating device. For this purpose tripping lever 49 is connected by means of a link 50 to a bell crank lever 51 (see Fig. 4), the other arm of which has a laterally projecting pin 52. This pin is engaged and lifted by the upper end of a vertical bar 53 which is fixed at 54 to the side of the elevating device so that when the elevating device is raised, bar 53 rises with it and engages pin 52, thereby tripping the fifth tripping lever 49.

With all five of the tripping levers 42 and 49 tripped, the latch bar 45 is released and can move upwardly under the tension of a helical spring 55 which is attached to the outer end of an arm 56 which is pinned to shaft 48. No motion of arm 56 takes place, however, unless, or until, roller 34 of arm 35 is engaged by the projection 36 of the actuating disc cam 27 because of the fact that the friction of the latch about to be described is too great. This latch is indicated by numeral 57 in Fig. 4 and is on the end of an arm 58 which is secured to the outer end of shaft 23. Latch 57 is engaged by a latch plate 59 on the end of an arm 60 which is loosely pivoted on shaft 48 near arm 56.

If the charge-assembling mechanism 2 is not filled with bottles, or if no case is in position to receive the charge, so that latch bar 45 is not released, at each rotation of actuating cam 27 when roller 34 rides onto projection 36, there is a slight rocking of shaft 23 which lifts latch 47 slightly away from the edge of latch plate 59, but the latch immediately settles into place again against the edge of plate 59 when roller 34 rides off from projection 36. When, however, there is a full charge of bottles in the charge-assembling mechanism and a case in proper position, latch bar 45 being thereby released, and when roller 34

rides onto projection 36, as soon as the friction between latch 57 and the edge of latch plate 59 is relieved by the raising of latch 57, latch plate 59 is immediately snapped to the right, as shown in Fig. 4, by means of tension spring 55, the force of this spring being transmitted to arm 60 by a pin 61 fixed to arm 56, the left-hand portion of which pin, as shown in Fig. 2, projects into and engages the bottom of a slot 62 in a link 63 which is pivoted to the side of arm 60.

As soon as latch 57 drops slightly below the edge of latch plate 59, a sloping cam surface 64 which projects from the side of arm 56 upon which latch 57 is mounted, strikes a roller 65 mounted near the end of arm 56, thus swinging arm 56 outwardly and rocking shaft 48 and resetting latch bar 45 beneath the latch 44 of latch levers 42 and 49, which have just previously been released by the descent of the charge of bottles into the case 20. This outward movement of arm 56 swings pin 61 outwardly within its slot 62, thus placing another helical spring 66 under tension. This clasps the face of latch plate 59 against the side of latch 57. It remains in this position until the shifting of the plates 18 is completed and they are returned to their normal position in alinement with the guide bars 6 by the continued rotation of cam 27 which brings projection 36 again into engagement with roller 34. When, however, during the final part of this movement latch 57 is again raised above latch plate 59, the tension of spring 66 causes the latch plate to return into holding position beneath the latch 57. This completes a cycle of operation of the charge-assembling and packing mechanism.

We shall now return to the case-feeding mechanism which is the subject matter of the present invention, and first of all refer briefly to the general sequence of operation.

The cases to be filled are delivered to the machine along the roller conveyor 1 sometimes in a continuous line in end-to-end contact with one another, and sometimes spaced apart by varying distances. The foremost case is received upon a short timer belt 67 which is continuously driven and which forces the front of the box against a stop 68, 69 consisting of a roller 68 and a pair of stop fingers 69. At the proper time the left-hand end of belt 67 is raised to free the case from the stop and the belt pushes the box over the stop onto a roller table 70 which, together with belt 67, is inclined at about the same slope as conveyor 1 and which extends through the machine and out at the left-hand side, as viewed in Figs. 5, 1 and 6. The case moves to the left along roller table 70 until it strikes a second stop roller 71, and in so doing, trips a release finger 72 which causes the elevating device indicated generally by numeral 13 to raise the case to the full line position shown in Fig. 5 as case 20. The case then receives its charge of bottles from the charge-directing mechanism 3 and descends to its original position on roller table 70 shown in dotted lines in Fig. 5. Thereupon the stop roller 71 is withdrawn downwardly from in front of the case, thus permitting the case to roll by gravity along the roller table out of the machine at the left-hand side where it may be discharged onto another conveyor, not shown, similar to conveyor 1 by which it is to be conveyed to the next operation or to a shipping or storage department.

The raising of timing belt 67 to lift the foremost case over the stop 68, 69, and the reset-

ting of stop roller 71 to its raised, or full-line, position, as shown in the drawings, are accomplished by means of a one-revolution clutch indicated generally by numeral 74 and shown in Figs. 4, 3, 6 and 7. This clutch comprises a short shaft 75 journalled in suitable brackets attached to the framework of the machine, a star wheel 76 which is integral with and driven by a sprocket 77, both of which are continuously driven by a chain 78 from low speed shaft 15 of the reduction gearing 12, and a clutch member 79 which is keyed to shaft 75, as indicated in Figs. 4 and 7. Also keyed to shaft 75 alongside of clutch member 79 is a cam 80 by means of which the desired actions referred to are produced, but which will be referred to more in detail presently.

The one-revolution clutch 74 is set in operation,—that is to say, cam 80 is given thereby a single rotation, by the movement of the stop fingers 69 to the left (Figs. 5, 6 and 7) by the pressure of the front face of a case on the timer belt. Such movement of these fingers can occur whenever the preceding case has been cleared from the packing machine, but not otherwise, and the mechanism for providing such control will be described later.

Stop roller 68 is provided with recesses 81 opposite these fingers, as shown in Fig. 6, both to permit this motion and also to enable the surface of the stop roller to assist timer belt 67 in lifting the front end of the case over the stop fingers 69. Since fingers 69 are fixed to a shaft 82 which extends crosswise of the roller table 10, their movement under the pressure of the front end of the case causes this shaft to rock slightly. On one end of this shaft opposite the one-revolution clutch 74, there is a downwardly extending arm 83 which is connected by means of a link 84 to a clutch control lever 85 which is loosely mounted towards the outer end of a cross shaft 86.

On the upper end of clutch control lever 85 there is a roller 87 which, in its normal position, engages the lower surface of the tail 88 of a dog 89, which is pivoted at 90 to one arm of clutch member 79. When stop fingers 69 are moved to the left, as shown in Fig. 7, by a case on timing belt 67, the upper end of clutch control lever 85 together with its roller 87 is moved in the same direction and disengages tail 88, thereby permitting dog 89 to be pulled into engagement by means of a helical spring with the continuously rotating star wheel 76.

Shaft 75 and cam 80 are thus started on their single revolution in the direction of the arrow shown in Fig. 7. Shortly after the tail 88 of dog 89 is carried around sufficiently by the rotation of the shaft to be clear of roller 87, this roller is moved back into its original position by the movement of clutch control member 85, as will also be described later on. Therefore, as soon as shaft 79 completes a single revolution, tail 88 again engages roller 87, thus pulling the head of the dog out of engagement with the star wheel 76 and causing the rotation of shaft 79 to stop. In order to prevent back lash, a spring-pressed latch lever 91, which is raised by the rotation of arm 92 of the clutch member 79, snaps back against the rear side of this arm just as the single revolution is completed.

Cam 80 is provided with a single, relatively narrow projection, as illustrated, which as it commences to rotate at first engages a roller 93 which actuates resetting mechanism later to 75

be described, and immediately thereafter a second roller 94. This roller effects the raising of the left-hand end of timer belt 97 which frees the case from the stop 68, 69 and permits it to enter the packing machine. For this purpose, roller 94 is mounted upon the end of a short arm 95 which is fixed to the outer end of a rock shaft 96 which extends crosswise beneath roller table 70. Also fixed upon this shaft beneath the roller table are a pair of arms 97, and at the outer ends of these arms there are two links 98 which serve to raise shaft 99 of a roller 100 over which the left-hand end of timer belt 67 passes. Shaft 99 is held in proper spaced relation from shaft 101 upon which the driving roller for belt 67 is mounted by means of a pair of spacer rods 102. Shaft 101 is driven by means of a chain 103 from a sprocket 104 also on the low speed shaft 15 of reduction gearing 12.

20 The case which has been elevated by timer belt 67 over the stop 68, 69 slides by gravity along the inclined roller table 70 until it strikes finger 72 and stop roller 71, the latter being appropriately positioned to place the case vertically below the charge-directing mechanism 3. Both stop roller 71 and finger 72 are carried between a pair of crooked arms 105, one at each side of the roller table 70, and pinned upon a rock shaft 106 which is journalled in the frame members 107 which support the rollers of this roller table. The crooked arms 105 slope upwardly toward the right, as shown in Figs. 5 and 10, and then turn vertically downward. At about the point where they turn downward, they are provided with bosses 108 in which the bearings of stop roller 71 are journalled. A short distance below this point they are provided with a second set of bosses 109 in which a rock shaft 110 is journalled and at the center of which finger 72 is fixed. The movement of finger 72 by the case rocks shaft 110 and causes a pair of arms 111 at each end of the rock shaft to raise pins 112 which project laterally from the sides of the short arms of a pair of bell crank latch levers 113. This swings the longer arms of these bell crank levers to the left, as shown in Figs. 5 and 10, thereby disengaging them from the elevating device 73 and causing this device to move upwardly raising the case from its position on the roller table 70 into charge-receiving position with respect to the charge-directing mechanism 3.

55 The elevating device 73 comprises a pair of vertical rods 114 which are arranged to move vertically in suitable slide bearings 115 which are mounted upon the machine casing. At their upper ends, each of these rods has fixed thereto a horizontal member 116 shown in full lines in Fig. 2, and secured between these horizontal members at equal distances from the rods 114 are two lifting bars 117 which serve to lift the case. These bars are narrow enough to pass freely between the rollers of roller table 70 and are offset downwardly at their central portion between the frame members 107, as shown in Fig. 4, so that their upper surfaces are below the tops of the rollers of the roller table in the normal down position of the elevating device.

60 The elevating device 73 is raised by means of a weight 118 which is connected to the lower ends of the vertical rods 114 by means of an appropriate system of levers. This system includes a lever 119 to which the weight is attached and which is fixed upon a cross shaft

120. This shaft is journaled in suitable brackets secured to the machine frame and near its outer ends is provided with a pair of arms 121 which are slotted at their ends to engage respectively a pair of pins 122 which project inwardly from bosses 123 on the sides of the vertical rods 114 near their lower ends. The bell crank latch levers 113 engage these same pins 122. It will be understood, therefore, that when these latches are released by the engagement of the case with fingers 12, weight 118 will descend from the dotted position shown in Fig. 5, to the full line position, thereby raising the elevating device 73 and carrying the case into charge-receiving position.

It is important that the case be elevated to the proper level with respect to the charge-directing mechanism 8 on account of the flexible plates 124 and the flexible fingers 125 with which the charge-directing mechanism is provided. The level to which the case is elevated is adjusted by adjusting the horizontal position of a stop member 118' against which the weight 118 rests when in its lowermost position. These yieldable plates 124 extend downwardly below the top of the case when a case is being filled which is not provided with cell divisions, or when the partitioning devices do not extend to the top of the case. In the case which is illustrated, however, the partitioning devices forming the individual compartments for the bottles extend clear to the top of the walls of the case itself and therefore only the flexible fingers 125 project downwardly below the top of the case and the top of the partitioning devices when the case is in proper filling position.

These flexible fingers 125, it may be explained, are provided for the purpose of guiding the individual bottles into their individual compartments and preventing the bottoms of the bottles from impinging against the tops of the partitioning devices. Also when the partitioning devices are made of yieldable, or flexible, material such as paper, fibreboard, corrugated board, or the like, fingers 125 serve to shift these yieldable partitions into proper position. Fingers 125 are mounted in part on the lower edges of supporting rails 16 and in part on transverse parallel plates 126 shown in Figs. 4 and 5 and positioned at right angles to rails 16 and 17 and arranged on the same spacing as these rails and thereby subdividing the spaces between the rails into individual bottle chutes. These plates 126 are preferably provided with V-shaped notches in their upper edges as shown in Fig. 5, which assist in separating the individual bottles of each row as the charge descends through the charge-directing mechanism into the case.

As soon as the case is elevated by the elevating device 73 out of the dotted position shown in Fig. 5, finger 12 is released and is returned to its normal position by means of a pair of helical springs, the upper ends of which are connected to the short horizontal arms of the bell crank latches 113. These springs move these latches back into position to be engaged by the pins 122 as soon as the elevating device again descends. Through pins 112 pressing downwardly on arms 111, these springs also force these arms downwardly against their stop pins 121 which are carried in suitable projections from the projections on the crooked arms 105, and this movement returns finger 12 to its normal position.

As soon as the case 20 is elevated by the

elevating device 73, assuming that a complete charge of bottles is already within the bottle-assembling mechanism 2, the raising of bar 53, which is attached to the elevating device 73, into contact with pin 52 of bell crank 51 causes the releasing of the mechanism which shifts plates 18 to the right, as shown in Fig. 5 and causes the charge of bottles to descend into the case. The weight of the charge overbalances the weight 118 and causes the elevating device 73 to be lowered to its original position in which it is latched and held by the bell crank latches 113 re-engaging the pins 122.

During the final downward movement of the elevating device 73, the latch mechanism is tripped, which causes the stop roller 71 to drop below the front corner of the case and the case rolls forward by gravity along the roller table 70 and out of the machine. This mechanism comprises a latch bar 128 which is pivoted to the frame at 129 and held in the position shown in Fig. 5 by means of a spring 130. In this position the latch engages a short arm 131 which is fixed to the outer end of rock shaft 106 to which crooked arms 105 are secured. To release this latch, bar 53 which is carried by the cross head of elevating device 73 is provided with a downward extension shown in Figs. 5 and 10 at the lower end of which is a laterally projecting pin 132. This pin, at the very end of the downward movement of elevating device 73, engages a laterally projecting cam surface 133 (Figs. 9 and 6) which is carried by latch bar 128 in a manner which will be presently described. Pin 132 forces this cam surface both downwardly and to the right, as shown in Figs. 9 and 5, and before reaching the end of its down movement, pin 132 passes by the left-hand end of cam surface 133 and releases the same. The downward swing of latch lever 128 caused thus is sufficient to release the latch from its engagement with the short arm 131, and the release of the cam surface 133 by pin 132 permits the latch to be immediately returned to relatchable position against the rounded surface of the right-hand side of arm 131.

In order to permit pin 132 to move upwardly on the next operation of elevating device 73, cam surface 133 is not fixed directly to the side of latch bar 128 but is fixed to a small lever 134 which is pivoted on the side of this latch bar and normally held in position against a stop pin 135 by means of a helical spring 136. On the downward movement, the force of pin 132 is transmitted through cam surface 133 and the small lever 134 to pin 135 and thence to latch bar 128. On the upward movement pin 132 engages the lower side of cam surface 133 and swings lever 134 freely about its pivot tensioning spring 136 which returns the lever against the stop pin as soon as it has been released.

The release of the short arm 131 by latch bar 128 enables a tension spring 137 aided by gravity to swing the crooked arms 105 and stop roller 71 downwardly below the surface of the rollers of roller table 70 and out of the path of the case. This downward position of these parts is illustrated in dotted lines in Fig. 5. This carries arms 111 of the finger 12 mechanism downwardly out of operative engagement with pins 112, but they are returned to operating position before they are required to release the elevating device for the next succeeding case, as will appear presently.

As hereinbefore mentioned, a new case must

not be fed over the stops 68, 69 until the preceding case has been filled and ejected from the machine. In order to provide against this, a locking arm 138 is provided on the clutch control lever 85 for the one-revolution clutch. This arm is fixed to the same hub from which the lower and upper arms of the clutch control lever project, so that by holding locking arm 138 against downward movement, roller 87 is held beneath the tail 88 of the dog 89 of the one-revolution clutch, and fingers 69 are prevented from moving under the pressure of the forward end of the case and therefore serve as stops so long as this status quo is maintained. In order to lock arm 138 against downward movement, a long rod, or pin, 139 (Fig. 3) is secured to an extension 140 at the lower end of one of the crooked arms 105 of the mechanism for supporting the stop roller 71. Hence, as long as stop roller 71 is in its upward position in which it holds a case upon roller table 70, this rod 139 by engaging locking arm 138 causes fingers 69 to serve as stops holding back on the timing belt 67 any case which presents itself on this belt before the carton 20 has been lowered and cleared from the machine.

As soon, however, as carton 20 has been released by the dropping of stop roll 71, rod 139 drops away from locking arm 138 so that if a carton is resting against stop 69, or as soon as a case engages this stop, the one-revolution clutch is again actuated to feed the case into the machine. The first action of cam 80 after being set in motion by the tripping of the one-revolution clutch, however, is to reset stop 71 in its normal or uppermost position, so that the stop will be ready to receive the succeeding case as soon as it is delivered over the stops 68, 69. The mechanism for such resetting is as follows:

As mentioned above, cam 80, when its rotation commences upon the tripping of the one-revolution clutch, first engages a roller 93 and then the roller 94 which actuates the lifting mechanism for timing belt 67. Roller 93 actuates the resetting mechanism and for this purpose is mounted upon a short arm 141 (Fig. 9) which is fixed upon cross shaft 86 adjacent cam 80. Fixed to this shaft at this same point, but extending in the opposite direction, and also fixed to the opposite end of shaft 86, are two longer arms 142 which are parallel with one another and which are tied together at their outer ends by means of a cross rod 143 (Figs. 6 and 4). Extending nearly vertically upward from cross rod 143 and inside of the frame members 107 of roller table 70 are a pair of links which, at their upper ends are provided with slotted portions 145.

These slotted portions receive the ends of the shaft 146 of the stop roller 71. When the stop roller 71 drops from in front of the filled case to allow the case to pass out of the machine, the bottoms of the slots in slotted portions 145 serve as stops to limit the downward movement of the stop roller and of the two crooked arms 105. It will be remembered that the final downward movement of the elevating device 73 causes pin 132 to engage cam surface 133 and trip the latch 128, thereby releasing it from arm 131 and permitting the dropping of the stop roller and the crooked arms under the action of spring 137.

Now, under the resetting action of cam 80 operating on roller 93, shaft 86 is rocked, raising arms 142 and slotted links 144, thereby lifting stop roller 71 to its original position above roller 75

bed 70 and causing latch bar 128 to re-engage itself behind the arm 131 and hold the crooked arms 105 and roll 71 in the raised position. As soon as roller 93 is disengaged by the projection 5 on cam 80, the resetting mechanism is again lowered leaving the upper end of the slotted portions 145 of links 144 resting on the shaft 146 of stop roller 71. This supports the various parts of the resetting mechanism and also leaves the 10 stop roller 71 free to descend when the next succeeding case is filled and ready to be discharged from the packing machine.

With the case-feeding mechanism which has been provided by the present invention, the cases 15 are automatically and successively brought accurately into proper registry with the charge-directing mechanism 3 which, in filling position, extends below the top of the case, and this is accomplished without bending, or otherwise manipulating any part of this charge-directing mechanism. The charge-assembling and packing mechanism is properly coordinated with the case-feeding mechanism, so that the cases are fed into the machine rapidly, as fast as the successive charges are assembled ready to be packed, but at the same time it is impossible for a charge to be released by the packing mechanism before the case is in its proper registry with the charge-directing mechanism.

30 A new case, that is, a succeeding case, cannot be fed into the machine until the preceding case has been packed and ejected. Hence, if the cases are fed to the machine in a continuous line in end to end contact, the line will be held 35 back by the fingers 69 serving as stops as long as the preceding case is either on the roller table 70 in front of stop roller 71, or on the elevating device 73. Moreover, it is impossible for the next succeeding carton to be admitted 40 to the machine until the carton discharging or ejecting mechanism has completed that function and been reset in proper position to receive the next succeeding case.

I claim:

45 1. In an article-packing machine, a charge-assembling mechanism, charge-directing mechanism for receiving an assembled charge and through which the same is dropped into a case, a conveyor for cases to be filled extending beneath the charge-directing mechanism, an elevating device for raising the cases one at a time 50 from the conveyor into charge-receiving position beneath the charge-directing mechanism, and feeding mechanism for delivering the cases one at a time to the elevating device comprising a stop roller positioned above the surface of the conveyor to engage the front end of the foremost case, said roller having a peripheral groove therein, means for simultaneously lifting and feeding the foremost case over said stop roller, and means 55 for controlling the actuation of said lifting and feeding means including a finger opposite the groove in the stop roller and normally positioned outside of the groove and adapted when engaged by the case to move into the groove to enable the stop roller to assist in raising the case over the top of said finger.

60 2. In an article-packing machine, charge-assembling mechanism, charge-directing mechanism for receiving an assembled charge and through which the same is dropped into a case, a conveyor for delivering beneath the charge-directing mechanism a continuous line of cases to be filled, elevating mechanism for raising a case from the conveyor into charge-receiving po-

sition with respect to the charge-directing mechanism, means for removing the filled case from the machine, means cooperating with the conveyor for feeding the cases one at a time into position to be elevated by the elevating device, and means for restraining the feeding mechanism from feeding a succeeding case to the elevating device until the preceding case has been removed.

3. In an article-packing machine, a charge-assembling mechanism, charge-directing mechanism for receiving an assembled charge and through which the same is dropped into a case, a conveyor for delivering a continuous line of cases to be filled beneath the charge-directing mechanism, elevating mechanism for raising a case from the conveyor into charge-receiving position with respect to the charge-directing mechanism, means for removing the filled case from the machine, means cooperating with the conveyor for feeding the cases one at a time into position to be elevated by the elevating device, and means actuated by the removing mechanism for restraining the feeding mechanism from feeding a succeeding case to the elevating device until the preceding case has been removed.

4. In an article-packing machine, charge-assembling mechanism for assembling a charge of articles in upright position and arranged in a geometric formation to correspond with the case to be filled, charge-directing mechanism for receiving the assembled charge and through which the same is dropped into the case, the charge-assembling mechanism including means for releasing the charge into the charge-directing mechanism, a conveyor for cases to be filled extending beneath the charge-directing mechanism, an elevating device for raising the cases one at a time from said conveyor into charge-receiving position with respect to the charge-directing mechanism, means operating during the final upward movement of said elevating device for actuating said releasing means thus causing the charge to drop into the case, and means for removing the case from the machine, said means being set in operation by the dropping of said charge.

5. In an article-packing machine a charge-assembling mechanism, charge directing mechanism for receiving an assembled charge and through which the same is dropped into a case, a conveyor for cases to be filled extending beneath the charge-directing mechanism, a pair of stops arranged in spaced relation on said conveyor and adapted to stop the advance of cases along said conveyor, an elevating device between said stops for raising the case thereover into charge-receiving position with respect to the charge-directing mechanism and for lowering the filled case to the conveyor, mechanism for releasing the foremost case on the conveyor from said first stop to cause it to advance into position over said elevating device, means actuated by the case adjacent said second stop for initiating the operation of said elevating device to cause the same to raise said case to receive a charge of articles and then lower the filled case to the conveyor, and means actuated by the final downward movement of the elevating device for withdrawing said second stop to permit said conveyor to carry the filled case out of the machine.

6. In an article-packing machine a charge-assembling mechanism, charge-directing mechanism for receiving an assembled charge and through which the same is dropped into a case, a conveyor for cases to be filled extending be-

neath the charge-directing mechanism, a pair of stops arranged in spaced relation on said conveyor and adapted to stop the advance of cases along said conveyor, an elevating device between said stops for raising the case thereover into charge-receiving position with respect to the charge-directing mechanism and for lowering the filled case to the conveyor, mechanism for releasing the foremost case on the conveyor from said first stop to cause it to advance into position over said elevating device, means actuated by the case adjacent said second stop for initiating the operation of said elevating device to cause the same to raise said case to receive a charge or articles and then lower the filled case to the conveyor, means actuated by the final downward movement of the elevating device for withdrawing said second stop to permit said conveyor to carry the filled case out of the machine, and means actuated by said releasing mechanism for resetting said second stop.

7. In an article-packing machine a charge-assembling mechanism, charge directing mechanism for receiving an assembled charge and through which the same is dropped into a case, a conveyor for cases to be filled extending beneath the charge-directing mechanism, a pair of stops arranged in spaced relation on said conveyor and adapted to stop the advance of cases along said conveyor, an elevating device between said stops for raising the case thereover into charge-receiving position with respect to the charge-directing mechanism and for lowering the filled case to the conveyor, mechanism for releasing the foremost case on the conveyor from said first stop to cause it to advance into position over said elevating device, means actuated by the case adjacent said second stop for initiating the operation of said elevating device to cause the same to raise said case to receive a charge of articles and then lower the filled case to the conveyor, and means for withdrawing said second stop to permit said conveyor to carry the filled case out of the machine.

8. In an article-packing machine a charge-assembling mechanism, charge-directing mechanism for receiving an assembled charge and through which the same is dropped into a case, a conveyor for cases to be filled extending beneath the charge-directing mechanism, a pair of stops arranged in spaced relation on said conveyor and adapted to stop the advance of cases along said conveyor, an elevating device between said stops for raising the case thereover into charge-receiving position with respect to the charge-directing mechanism and for lowering the filled case to the conveyor, mechanism for releasing the foremost case on the conveyor from said first stop to cause it to advance into position over said elevating device, means actuated by the case adjacent said second stop for initiating the operation of said elevating device to cause the same to raise said case to receive a charge of articles and then lower the filled case to the conveyor, means for withdrawing said second stop to permit said conveyor to carry the filled case out of the machine, and means for resetting said second stop.

9. In a machine of the character described, a conveyor for cases to be filled, an elevating device for raising the cases one at a time from the conveyor into charge-receiving position, and feeding mechanism for delivering the cases one at a time to the elevating device comprising a stop roller positioned above the surface of the con-

veyor to engage the front end of the foremost case, said roller having a peripheral groove therein, means for simultaneously lifting and feeding the foremost case over said stop roller, and means for controlling the actuation of said lifting and feeding means including a finger opposite the groove in the stop roller and normally positioned outside of the groove and adapted when engaged by the case to move into the groove to enable the stop roller to assist in raising the case over the top of said finger.

10. In a machine of the character described, a conveyor for a continuous line of cases to be filled, elevating mechanism for raising a case from the conveyor into charge-receiving position above the conveyor, means for removing the filled case from the machine, means cooperating with the conveyor for feeding the cases one at a time into position to be elevated by the elevating mechanism, and means actuated by the removing means for restraining the feeding mechanism from feeding a succeeding case to the elevating mechanism until the preceding case has been removed.

11. In a machine of the character described, a conveyor for cases to be filled, a pair of stops arranged in spaced relation on said conveyor and adapted to stop the advance of cases along said conveyor, an elevating device between said stops for raising the case thereover into charge-receiving position and for lowering the filled case to the conveyor, mechanism for releasing the foremost case on the conveyor from said first stop to cause it to advance into position over said elevating device, means actuated by the case adjacent said second stop for initiating the operation of said elevating device to cause the same to raise said case to receive a charge of articles and then lower the filled case to the conveyor, and mechanism for withdrawing said second stop to permit said conveyor to carry the filled case out of the machine.

12. In a machine of the character described, a conveyor for cases to be filled, a pair of stops arranged in spaced relation on said conveyor and

adapted to stop the advance of cases along said conveyor, an elevating device between said stops for raising the case thereover into charge-receiving position and for lowering the filled case to the conveyor, mechanism for releasing the foremost case on the conveyor from said first stop to cause it to advance into position over said elevating device, means actuated by the case adjacent said second stop for initiating the operation of said elevating device to cause the same to raise said case to receive a charge of articles and then lower the filled case to the conveyor, means for withdrawing said second stop to permit said conveyor to carry the filled case out of the machine, and means for resetting said second stop.

15. In a machine of the character described, a conveyor for cases and mechanism for controlling the advance of cases thereon comprising a stop roller positioned above the surface of the conveyor to engage the front end of the foremost case, said roller having a peripheral recess therein, means for simultaneously lifting and feeding the foremost case over said stop roller and means for controlling the actuation of said lifting and feeding means including a finger opposite the recess in the stop roller and normally positioned outside of the recess and adapted when engaged by the case to move into the recess to enable the stop roller to assist in raising the case over the top of said finger.

20. In a machine of the character described, a conveyor for cases and mechanism for controlling the advance of cases thereon comprising a stop positioned above the surface of the conveyor to engage the front end of the foremost case, means for simultaneously lifting and feeding the foremost case over said stop and means for controlling the actuation of said lifting and feeding means including a finger disposed adjacent said stop adapted to be shifted by the case as it moves against the stop, means connecting said finger with said controlling means and means for preventing the operation of said connecting means under predetermined conditions.
